UNITED STATES PATENT OFFICE.

WALLACE S. WARNOCK, OF CHICAGO, ILLINOIS.

PRINTING PRESS.

Application filed June 4, 1923. Serial No. 643,255.

The present invention pertains particularly to printing presses of the type employing an impression cylinder provided with a plurality of impression surfaces, and a plurality 5 of printing (plate) cylinders, said printing cylinders co-acting with all of the impression surfaces in multi-color printing and being capable of automatic alternate retraction when the machine is adjusted for printing 10 separate jobs for each printing cylinder.

An important object is to provide an organization of elements, whereby in heavy presses of this character, the shiftable printing-cylinders will be advantageously counterbalanced, whereby the mechanisms may be 15 nicely adjusted and will operate with dependable precision, and whereby the machine shall possess great durability.

A further object is to provide, in connection 20 with such an organization of elements, improved controlling devices for controlling the shifting of the printing cylinders, and preferably in connection with automatic sheet-feeding mechanisms, sheet-controlled 25 devices which automatically control said control devices, whereby the control of the retraction of the printing-cylinders and their return to the printing position is rendered automatic. To facilitate an understanding 30 of the machine from the detailed description which follows, it may be stated preliminarily that in the preferred construction shown the machine comprises: a large impression or tympan cylinder provided with two impression 35 surfaces, each having associated work-holding devices (grippers); a pair of printing-cylinders which are provided with shiftable bearings, or journal-boxes; a counterbalance spring connected with and tending 40 to lift each journal-box; a normally stationary (in two-color work) rock-shaft below each printing-cylinder having angularly adjustable end-sections equipped with eccentrics, the angular adjustment of said 45 end-sections serving to properly position the eccentrics; eccentric rods affording positive connections between the eccentrics and journal-boxes or carriers; a fixed actuating arm, or carrying arm, on each rock-shaft; a 50 pair of periodically oscillated actuators journalled on each rock-shaft, one of said actuators corresponding in its timing with one of the impression surfaces of the tympan cylinder and the other with the other; 55 coupling-links, or control members preferably mounted on the fixed arm (on each

side) and serving to couple the fixed arm to either oscillating actuator; a feed-mechanism and associated control mechanism corresponding with the related impression surface to which said feed-mechanism feeds sheets, the control mechanism associated with each feed-mechanism being adapted to successively trip the printing-cylinders to permit the corresponding impression surface 60 to pass the printing cylinders in case of mis-feed; and inter-acting control means whereby the cylinders retracted as a result of a mis-feed at one feed-mechanism will be held at retracted position long enough to 65 permit the passage of the other impression surface in case of mis-feed at the other feed-mechanism. Thus, it will be understood that there is associated with each feed-mechanism a control mechanism which is 70 automatically controlled when the sheet-feeding is done automatically. When the sheet-feeding is not done automatically, the 75 operation of the control mechanism may be non-automatic, if desired. That is, the tripping may, in such case, be manually controlled.

It may be added that by simple adjustment, the machine may be set to operate for independent jobs (one-color work), each 80 printing cylinder being then automatically retracted, in proper sequence, to permit the non-corresponding impression surface to 85 pass without contact.

The invention is illustrated in its preferred 90 embodiment in the accompanying drawings, in which—

Figure 1 is an elevation of a complete 95 press structure embodying the present invention;

Figure 2 is a side elevation of the upper portion of the press, showing an arrangement of trips co-operating with the feeding mechanism and operative on mis-feed;

Fig. 3 is a side elevation of the lower 100 portion of the press, with the housing broken away, this figure showing the tripping and locking mechanism operating on mis-feed in normal inoperative position;

Fig. 4 is a side elevation of the lower portion of the press with the casing partially broken away, similar to Fig. 3; the trip and lock mechanism being in this figure shown in operation, one printing roller being depressed and out of engagement with the impression cylinder;

Fig. 5 is a horizontal section through the

press on the line 5—5 of Figure 3, showing in plan a part of the tripping and locking mechanism;

Fig. 6 is an end elevation of the lower portion of the press, viewed from the right-hand end of Figures 3 and 5;

Fig. 7 is a detailed section on a horizontal plane looking down as indicated by the line 7 on Figure 3;

Fig. 8 is a vertical section on the line 8—8 of Fig. 5, looking in the direction of the arrows;

Fig. 9 is a vertical section longitudinally of a portion of the press on the line 9—9 of Fig. 8, viewed in the direction of the arrows;

Fig. 10 is a detailed elevation, partially broken away, taken at one end of the press and showing the interconnection between the inking roll carriage and the corresponding printing roll operating mechanism;

Fig. 11 is a detailed vertical section on the line 11—11 of Fig. 10;

Fig. 12 is a detailed view in side elevation of the safety locking mechanism on the printing roll carriage operating device, together with the parts associated therewith;

Fig. 13 is a plan view of the detailed parts shown in Fig. 12;

Fig. 14 is a detailed sectional view through a part of Fig. 13;

Fig. 15 is a sectional view on the line 15—15 of Fig. 12;

Fig. 16 is a detailed sectional view on the line 16 of Fig. 9; and

Fig. 17 is a detailed plan view of the trip finger employed to detect misfeed in the feeding device.

The press illustrated in the drawings is provided with a suitable frame work 25, in which is rotatably mounted the large impression cylinder 26, which receives paper from two feeding devices 27 and 28, preferably mounted on opposite sides of the press.

Feeding device 27 supplies paper to the impression roll 26 through the intermediary of the transfer roll 27^a. Feeding device 28 feeds paper directly to the impression roll 26. The feeding devices 27 and 28 are so timed as to feed paper alternately, when both are operating, at intervals of 180° on the impression cylinder 26. Cooperating with the impression roll 26 are two printing rolls 29 and 30, rotatably mounted respectively in shiftably mounted bearings or carriers 31 and 32. The carriers 31 and 32 are slidably mounted in similar sets of guides 33, and each of the printing cylinders is counterbalanced or yieldingly held upwardly

against the impression cylinder 26 by a suitable coil spring 34 acting against heads 35 mounted on rods 36 suitably secured to the carriers 31 and 32. The carriers 31 and 32 are adjustably connected by links 37 and 38 to the eccentric blocks 39 and 40. Within the

eccentric block 39 is rotatably mounted an eccentric 41, and in the eccentric block 40 a similar eccentric 42. The eccentrics 41 and 42 are mounted on short shafts 43 and 44 in a manner more fully hereinafter described. In the press illustrated in the drawings, two printing cylinders may be employed in printing on sheets fed from both feeding devices, for example, as in two-color work. In such work, the printing cylinders are normally held in engagement with the impression cylinder 26, and means are provided such that, when both printing cylinders are in operation, a misfeed on either feeding device will cause a downward movement and disengagement of each of the printing cylinders in succession for the proper period of movement of the impression cylinder 26. The printing cylinders are then successively moved into engagement again with the impression cylinder 26 in time to print upon the next sheet fed from the other feeding device.

As will be hereinafter described, the means for the control of the printing cylinders are so arranged that either printing cylinder may be used alone with one of the feeding devices, the other printing cylinder being then prevented from engagement with the impression cylinder, or the two printing cylinders may be used independently, each with one of the feeding devices and printing independently a different job.

As the various parts and elements constituting the necessary control mechanism are substantially duplicated for each of the printing cylinders 29 and 30, to avoid confusion and complication of the drawings, those involved in the operation of only one of the printing cylinders are shown in detail. A similar set of parts in reverse position on the press is provided for the other printing cylinder.

Stud shaft 43 is coupled to a shaft 43^a, which is longitudinally aligned with it, by means of a suitable coupling 45, which is formed as a sleeve 45^a with a projecting yoke 46, each side of which is provided with a threaded bolt 47. The ends of the bolts 47 engage a pin 48 which projects from the eccentric 41. By means of the bolts 47 the relative angular positions of the shaft 43^a and the stud shaft 43 can be closely adjusted.

Keyed to the shaft 43^a is a carrier lever 49 or fixedly secured actuating arm having extended sleeves 49^a on each side. The movement of this carrier lever causes movement of the shaft 43^a and with it of the eccentric controlling the carrier for the roll 29. At the sides of the carrier lever 49 the operating levers 50 and 51, respectively, are pivotally mounted on the extended sleeves 49^a as hubs. These levers 50 and 51 are periodically oscillated on the sleeves 49^a, the former through a link 52 from a cam follower 53

pivoted on shaft 54 and the latter through a link 55 by cam follower 56 mounted on shaft 57. Cam followers 53 and 56 are provided with pins 58 which project into a suitable 5 cam race on the cam wheel 59 mounted on a counter-shaft 60 constantly driven through gears 61 and 62 from the main drive shaft 63. It will be noted from the drawings that the pins 58 projecting from the cam followers 53 and 56, respectively, into the cam race on the cam wheel 59 are substantially diametrically opposite, so that they are oscillated by the cam at 180° intervals. These intervals are so adjusted by the train of 10 gearing as to correspond to 180° intervals of the rotation of the impression cylinder 26. It will thus be apparent that the control levers 50 and 51 are oscillated at intervals corresponding to 180° intervals of the 15 rotation of the impression cylinder 26. At the proper period in its oscillation, either of the control levers 50 or 51 may be interlocked with the carrier lever 49 by means hereinafter fully described.

20 25 The interlocking or coupling of the oscillating operating lever 50 with the carrier lever 49 is primarily effected by means of a control member or coupling member 64 pivoted at 65 near one end of the carrier lever 49. At this end, as is apparent from the drawings, the carrier lever 49 expands fan-wise. The operation of this control lever is determined by secondary locking devices, the operation of which is hereinafter set forth.

30 35 This control member 64 is provided with an inner curved surface 64^a in which is formed a notch 64^b. At its end, the oscillating lever 50 is provided with a projecting pin 50^a, which rides over the curved surface 64^a of the control member 64 when the latter is in its normal inoperative position, as shown, for example, in Fig. 3. In the interlocking position of the control member 64, the pin 50^a engages in notch 64^b, as shown in 40 45 Fig. 4, the oscillating lever 50 and the carrier lever 49 being thereby interlocked. A coil spring 66 between the control member 64 and the carrier lever 49 tends to force the control member 64 inwardly into interlocking 50 55 position. In a similar manner, a second control member 67 is provided on the opposite side of the carrier lever 49 and it operates in a similar manner with the oscillating lever 51. The control members 64 and 67 are shown in elevation on opposite sides of the carrier lever 49 in Fig. 7.

60 65 Associated with each of the control members 64 and 67 are corresponding latch levers 68 and 69, respectively. The latch lever 68 is pivoted at 70 on the carrier lever 49 and is provided with a downwardly depending arm 68^a which, when the control member 64 is in its normal inoperative position as in Fig. 3, engages a shoulder 64^c formed on the control member 64. A coil spring 71 extends

70 between the control member 64 and the latch lever 68, tending to hold the arm 68^a of the latch lever 68 in engagement with the shoulder 64^c. The latch lever 68 thus normally serves to latch the control member in inoperative position, so that the oscillating lever 50 may oscillate freely without carrying with it the carrier lever 49. On the opposite side of the carrier lever 49, the latch lever 69, which is constructed similarly to the 75 latch lever 68, operates in a like manner.

75 It is thus apparent that the operation of the carrier lever 49 and with it of the printing roll 29 is controlled for a period of 180° of the movement of the impression roll 26 by the control member 64 and the latch lever 68 and for the other period of 180° of the rotation of the impression roll 26 by the control member 67 and the latch lever 69.

80 85 The immediate control of the depression of the printing rolls being thus made clear, the properly timed operation of these control devices from the feeding mechanism will now be considered.

85 90 Considering first the feeding device numbered 27, and referring more particularly to Figs. 2 and 17, when a sheet of paper is properly fed by the feeding device 27, it passes between a trip finger 72 and a plate 73, in which is formed a notch 74. The trip finger 72 is loosely connected at one end with an oscillating lever 75 adjustably mounted on a short arbor 76, this arbor being suitably journaled in a supporting bracket 77. Secured to this arbor is another lever 78, the end of which is connected by means of a link 79 to a lever cam follower 80 mounted on a stud shaft 81. This cam follower is provided at one end with a roller 82 which follows the surface of cam 83. The lever 80 is provided with an additional arm 84 which is connected by means of a link 85 with a bell crank lever 86 pivoted on the supporting frame of the machine. A coil spring 87, connected between one arm 100 105 of the bell crank 86 and the supporting frame of the machine, tends to hold the cam follower 82 of the cam lever 80 in engagement with the surface of cam 83. The bell crank lever 86 is connected by means of a link 88 with a push rod 89, the function of which will be hereinafter explained. It will be apparent that the rotation of the cam 83 causes a periodic oscillation of the lever cam follower 80 and with it of the arbor 76. This results in a periodic to-and-fro movement of the trip finger 72, which continues as long as paper is fed properly between it and the notched plate 73. At the same time, the push rod 89 is periodically swung backward and forward by means of the bell crank lever 86. The cam surface of a second rotating cam 90 engages a roller 91 at one end of the bell crank lever 92 pivoted to the supporting frame of the machine at 93. At its 110 115 120 125 130

other end this bell crank lever is provided with a push plate 94 which, under suitable conditions, may engage the end of push rod 89. The bell crank lever 92 is held against the surface of the cam 90 by means of the coil spring 95 and consequently the bell crank lever 92 is likewise periodically oscillated. The normal oscillations of the cam follower lever 80 by means of the cam 83 and of the cam follower lever 92 by means of the cam 90 are so timed that the push rod 89 is not normally engaged by the bell crank lever 92. The periodical oscillations of the cam lever 80 and the bell crank lever 92 are so timed as to occur as each sheet to be printed upon is fed by the feeding device 27 to the press; that is, once for each revolution of the impression roll 26.

In case of mis-feed, however, the smooth surface of a sheet of paper is not interposed between the trip finger 72 and the notched plate 73, with the result that the trip finger, after its back stroke, is retained against forward movement by the notch 74. When this occurs, the cam lever 80 is held away from the lower portion of the race of the cam 83 and, through link 85, bell crank lever 86 and link 88, the push rod 89 is held in position to be engaged by the downward stroke of the bell crank lever 92. The downward movement of the push rod 89 is communicated to a lever 96 mounted on shaft 96^a. This movement of the shaft operates lever 96^b, connected with the shaft, resulting in an upward pull on the link 97, which is connected to an oscillating lever 98 secured to the shaft 99. Upon the same shaft is mounted a projecting lever 100, from which depend two links 101 and 102, to the ends of which are secured the loops 103 and 104. Within these loops lie the ends of the push rods 106 and 107, respectively. The other end of push rod 106 is connected to a lever 108 secured to shaft 109. As will be hereinafter pointed out, this lever 108 controls the initial operation of the latch lever 68 mounted on the carrier lever 49. The other push rod 107 is connected at its end to a similar lever 110 secured to a sleeve 110^a on shaft B 109, the operation of which lever substantially duplicates that of lever 108 and will consequently not be more fully hereinafter described. When the trip finger 72 is operated by a misfeed, as has already been pointed out, the link 97 is raised for the period of dwell of the cam 90. Through the mechanism just described, that is, the link 97, the oscillating levers 98 and 100 and the links 101 and 102, the push rods 106 and 107 are raised for corresponding periods. The rise of the end of push rod 106 brings it into position to be engaged by the hammer 111 mounted on the cam follower 112, which is pivotally mounted on shaft 113. Cam follower 112 is operated by cam 114 mounted on

the counter shaft B 60, which is driven by suitable gearing from the drive shaft 63. A second cam follower 116, operated by the same cam 114, is provided with a similar hammer 117, which engages the end of the push rod 107 when the latter is raised. The cam followers 112 and 116, both of which are mounted on the shaft 113, are so disposed as to operate with an angular difference between them corresponding to the angular difference in position of the printing rolls 29 and 30 with relation to the impression roll 26. The cam follower 112, through the lever 108, initiates downward movement and disengagement of the printing roll 29; and the cam follower 116, through push rod 107 and lever 110, performs a like function for the printing roll 30. By the proper timing of the cam followers 112 and 116, a proper timing of the operation of the printing rolls is in part secured.

When the push rod 106 is engaged by the hammer 111 on the cam follower 112, it actuates the lever 108 and with it the lever arm 108^a, also secured to shaft 109. A roller 108^b on the lever 108^a engages the arm 68^b of the latch lever 68, thereby throwing the end of the arm 68^a of the latch lever 68 out of engagement with the shoulder 64^c on the control member 64. The latter is thereby unlocked, and, when the roller 50^a on the oscillating lever 50 comes opposite the notch 64^b in the control member 64, the latter moves upwardly into engagement with the oscillating lever.

At the same time that the lever 108 is operated by the push rod 106, and with it the lever 108^a, a roller 119 on the former engages the projecting end 120 of the long arm of lever 121, which is pivotally mounted on shaft 122. The lever arm 121 is provided with a shoulder 121^b which engages an interlocking shoulder 49^a formed on the carrier lever 49. The shorter arm 121^a of lever 121 projects downwardly and is engaged by a coil spring 123, which normally tends to hold the shoulder 121^b on the opposite end of the lever in engagement with the shoulder 49^a. These interlocking shoulders 121^b and 49^a are engaged in the normal inoperative position of the carrier lever 49, but are disengaged by the movement of the lever 121 resulting from the operation of the push rod 106 at the same time that the latch lever 68 is operated to permit release of the control member 64. Thus at the same time that the carrier lever 49 is interlocked with the oscillating lever 50 by the control member 64, the carrier lever is released from engagement with the lever 121 and its movement is permitted.

A similar set of controls is provided on the opposite side of the carrier lever 49 for the operation of the control member 67 on the opposite side, these controls being effec-

tive upon misfeed at the feeding device 28. In order to prevent operation of both control members 64 and 67 at the same time, means are provided for locking one of them 5 in inoperative position while the other is operated. It will be noted from the drawings (particularly Fig. 12) that the control members 64 and 67 terminate in a somewhat pointed end at 64^c and 67^c, respectively. On 10 the carrier lever 49 is mounted a rock plate 124. This rock plate is pivotally mounted in a notch formed in the carrier lever 49 upon a shaft 125 which is supported in the carrier lever 49 at the two ends of the notch, 15 that is, at 126 and 127 (Figs. 12 to 15). The member 124 has a limited rocking movement. When it is engaged by the control member 67, the end 67^b of the latter slides under the rock plate 124, lifting that side of the rock 20 plate, as shown in Figs. 12 and 15. This movement depresses the opposite side of the rock plate to a position in which it locks the end 64^c of the control member 64, preventing the latter from engaging the oscillating lever 25 50. Similarly, if the control member 64 is the first to be operated, its action upon the rock plate 124 locks out of position the control member 67.

In the operation of the trip mechanism, 30 after the latch lever 68 and the carrier locking lever 121 have been released by the action of the push rod 106, control member 64 engages oscillating lever 50, thereby locking the carrier lever 49 thereto. Consequently, 35 in the next downward movement of the lever 50, the carrier lever 49 is carried with it, thereby rotating shaft 43^a and with it the eccentrics controlling the movement of the carriage 31 supporting the printing roll 29. The movement of the eccentric causes a 40 downward movement of the printing roll, the parts being brought to the position shown in Fig. 4.

After the roll has been depressed by the 45 action of the oscillating lever 50 and the control member 64, unless the control member 64 is withdrawn from engagement with the pin 50^a of the operating lever 50, by means hereinafter described, the carrier lever 49 begins to return with the operating lever 50 and the printing cylinder 29 consequently begins to rise into engagement with the impression cylinder 26. As the carrier lever 49 reaches the upper limit of its movement, the shoulder 121^b on the lever 121 snaps into interlocking engagement with the shoulder 49^a. As this occurs, the cam follower 128, actuated by cam 129 on shaft B 60 retracts a link 130 which is secured at its opposite end to a lever 131. A roller 132 on this lever then engages the shoe or trigger 64^a of the control member 64, pulling it down until the arm 68^a of the latch lever 68 engages the shoulder 64^c, thereby locking the 65 control member 64 out of engagement with

the carrier lever 50. The control member 64 is then again in normal inoperative position, and the periodic oscillations of the operating lever 50 do not carry with them the carrier lever 49.

In the further consideration of the operation of the press, it will be necessary to refer to various control elements, the operation of which is determined from the feed 28, and likewise to refer the various elements controlled from both feeds 27 and 28 and determining the operation of the printing cylinder 30. In so far as these elements do not relate to the operation of the printing cylinder 29, parts operating from the feed 28 or controlling the printing roll 30 are indicated by the same reference numerals as the corresponding parts controlled from the feed 27 and operating the printing cylinder 29, with the prefix B. It has already been explained that the apparatus shown on the drawings in so far as it relates to the operation of the printing cylinder 29, is completely duplicated on the opposite side of the press for the control of the printing cylinder 30. Thus, as regards the printing cylinder 30 the shaft B 60 functions in the same manner as the shaft 60 with respect to the printing cylinder 29. Similarly, the shaft B 43^a functions with respect to printing cylinder 30 in the same manner as the shaft 43^a with respect to the cylinder 29. The manner in which the operation of the cam follower 112 and the push rod 106 controls the operation of printing cylinder 29 has already been explained. Cam follower 116, through push rod 107, controls a precisely similar set of elements which, if viewed from the opposite side, would present an aspect identical with that shown in the figures of the present drawing. It is thus apparent that a mis-feed from the feeding element 27 will cause first a downward movement of the roll 29 initiated by the action of the cam follower 112 and subsequently a downward movement of the roll 30 in precisely the same manner, initiated by the movement of the cam follower 116. The timing of these movements will follow the timing of the various operating parts, and as indicated in connection with cam followers 112 and 116, will correspond to the angular difference in position of the printing cylinders 29 and 30 with respect to the impression cylinder 26.

It will be noted that certain of the elements included in the set of controls operated from the sheet 26 differ in conformation from the corresponding elements co-operating with the feed device 27. The functions in the manner of operation of corresponding parts are, however, identical. It will, therefore, be clear that mis-feed on the feeding device 28 is transmitted through the various control elements to the link B 97, which is raised and by its rising

movement operates a set of push rods, similar to the push rods 106 and 107, one of these push rods causing the operation of printing cylinder 30 in the manner which 5 has just been described for the operation of the parts under the control of the push rod 106. The other push rod, which plays a function similar to that of the push rod 107, has its movement transmitted through a 10 sleeve B 110^a on the shaft 109 to a lever 133 (see Figs. 5 and 6) which lever controls the operation of the control member 67 in precisely the same manner as the lever 108 controls the operation of the control member 15 64. The control member 67 then locks the operating lever 51 into engagement with the carrier lever 49 and a set of movements precisely similar to that which has already been described then takes place, the printing cylinder 29 being depressed and again returned to its proper printing position. Since the cam follower 56, which operates the oscillating lever 51, is so timed as to operate 180° behind the cam follower 53, the sequence of 20 operations is 180° on the impression cylinder later than the series of operations controlled by the control member 64. In other words, the operation as to each of the printing cylinders is timed at intervals corresponding to the intervals separating the 25 feeding of the sheets from the feeding devices 27 and 28.

When, by reason of a mis-feed of the feeding device 27, in two-color operation, the roll 29 has been depressed, if there is a mis-feed 30 at the other feeding device 28, special means are provided for maintaining the printing cylinder 29 depressed for the period of 180° of the rotation of the impression cylinder 35 corresponding to the second misfeed. It will be noted from the drawing that the rising movement of the link B 97 controlled by the trip on the feeding device 28, operates not only the lever on B 98 on the shaft B 99 and 40 through it effects the depression of the printing roll 30; it also operates a link 133 which is connected to a lever 134 mounted on shaft 135 positioned just below the shaft 99. Near this shaft is positioned a rod 136, the lower 45 end of which is secured to a lever 137 mounted on a shaft 138. At the upper end of the rod 136 a spring 140, secured at one end to the end of the rod and at its other end to a cross bar 141, tends to pull the rod 136 outwardly and upwardly into such position that the shoulder 136^a formed thereon may be engaged by a pin 134^a mounted at one end of the lever 134. In the normal inoperative 50 position of the carrier lever 49, a shoe 139 mounted on an extended arm of the carrier lever presses against the rod 136 and holds it in a position in which the shoulder 136^a cannot be engaged by the end of the lever 134. When, however, the shoe 139 on the 55 carrier arm 49 no longer engages the rod

136 by reason of the movement of the carrier lever 49 induced by a misfeed in the feeding device 27, the rod 136 is pulled out by spring 140 to a position in which it may be engaged by the pin 134^a. If at this time a misfeed 60 in the feeding device 28 occurs, as has previously been stated, movement is transmitted through rod 133 to the lever 134, resulting in a downward movement of the end of the lever 134, the end of which engages rod 136. 65 The latter is forced downwardly and with it the end of the lever 137 to which the rod 136 is secured. To the other end of this lever is secured one end of a link 142, the other end of which is pivoted to a link 143 70 which in its turn is pivoted to a cam follower 144 mounted on the shaft 128^a on which cam follower 128 is also mounted. (See Fig. 8.) A projecting pin 143^a is secured to the link 143 at the point of connection with the link 142. Pivotally mounted to a shaft 146 is a lever 147 which is provided with a projecting hooked arm 147^a. It is also provided with a downwardly depending arm 147^b which is normally in a 75 position to be engaged by the pin 143^a on the link 143 when the latter is raised. When the control member 64 is in the position shown in Fig. 4 by reason of a misfeed on the feeding device 27, the movement of the 80 lever 137 resulting from a misfeed in the feeding device 28 lifts the end of the link 143 and causes the pin 143^a to engage the arm 147^b of the lever 147. The periodical to-and-fro movement of the link 143 caused by the cam follower 144, occurring at this time, causes the depending arm 147^b of the lever 147 to be retracted, thereby drawing down the hooked arm 147^a into engagement with a pin 64^a on the control member 64 and 85 forcing the control member 64 downwardly. The latter is thereby released from engagement with the operating lever 50 and brought into a position in which the arm 68^a of the latch lever 68 engages the shoulder on the control member and locks it into its normal inoperative position. At the same time that this occurs, the movement of the lever 147 is transmitted through a link 148 90 to a lever 149 which is secured to shaft 151. The movement of the lever 149 is transmitted through the shaft 151 to a lever arm 152 (see Fig. 9). Prior to this movement, the latch lever 69 mounted on the opposite side of the carrier lever 49 from the latch lever 68 and co-operating with the control member 67 in the same manner that the latch lever 68 co-operates with the control member 64, has been interlocked with the control member. One arm of the latch lever 69 projects into the path of movement of a roller 153 mounted on the arm 152. The upward movement of this arm, induced by the movement of the link 148 resulting from the 95 movement of the lever 147, raises the arm of 100

the latch 69 and unlocks the control member 67, thereby engaging the carrier lever 49 with the operating lever 51. The control member 64 being locked in inoperative position and the control member 67 being in its operative position, the carrier lever 49 partakes of the movement of the latter lever for a complete oscillation, resulting in a depression of the printing roll 29 during the period of operation of the impression cylinder 26 corresponding to the misfeed in the feeding device 28. In the rising movement of the carrier lever 49 during the oscillation of the operating lever 51, the control member 67 is released from the operating lever 51 in the manner already described for the normal release of the control member 64 from the operating member 50. That is, the depending arm of the control member 67 engages a lever 154 disposed on the opposite side of the plane of the carrier lever 49 from the lever 131 and operating in precisely the same manner through a link 155 from a cam follower 156 controlled by a cam 157 on the shaft B 60.

If the first misfeed had been on the feeding device 28, it would have been communicated through the link B 97 and the lever B 98 to a push rod (not shown) operating on the lever 133 on the sleeve B 110 on shaft 109, and simultaneously would have operated the lever 121 to release the carrier lever 49 in the manner already described for the lever 108. In the manner already described for the operation of the operating lever 50 and the control member 64, the operating lever 51 and the control member 67 would have been affected, resulting in a downward depression of the printing cylinder 29 during the period corresponding to the oscillation of the operating lever 51; that is, to the 180° period of rotation of the impression cylinder 26 corresponding to the time of feeding by the feeding device 28. If at this time a misfeed had occurred in the feeding device 27, it would have been communicated through the rod 97 in the manner already described to the lever arm 98 on the shaft 99. This would have been communicated through a link 160 to a lever 161 mounted on the shaft 135. This lever co-operates with a rod 162 in the same manner that the lever 134 co-operates with the rod 136. As a result of the downward movement of the rod 162 resulting from the movement of the lever 161, the lever 163 is actuated, drawing the link 163^a upwardly and with it the link 164 which is secured to the cam follower 165 mounted on the shaft B 60, which causes a periodical oscillation of the cam follower and a two-and-fro

movement of the link 164. When the link 164 is raised by the lever 163, a pin 167 secured to its end, is drawn up behind a depending arm 168^b of a lever 168 pivoted to shaft 146, this lever corresponding in operation and function as regards the control member 67 to the lever 147 as regards the control member 64. In Fig. 9 these parts are most clearly shown, the control member in this figure being shown interlocked with the operating lever 51, the downward movement of the carrier lever 49 being about to begin. Under the conditions just described, the carrier lever 49 would be at the bottom of its movement, and the pin 67^a on the control member 67 would be in position to be engaged by the hooked end of the lever 168. The movement of the lever 168 resulting from the movement of the link 164 would thereupon release the control member 67 from the operating lever 51, permitting the latter to oscillate freely. The movement of the lever 168 would simultaneously cause a movement of the link 169 connected to the lever 170 mounted on the sleeve 150 mounted on the shaft 151. As seen from Fig. 16, the movement of the lever 170 is communicated through the sleeve 150 to a lever 171 provided with a projecting pin 172. This movement of the lever 171 trips the latch lever 68 which locks the control member 64 out of engagement with the operating lever 50, permitting the control member to engage the operating lever 50. As a result of this movement, for the next period of 180° of movement of the impression roll the carrier lever 49 partakes of the oscillatory movement of the operating lever 50, resulting in a second depression of the printing cylinder 29 for that period.

In order to adjust the device for single color work, three adjustments are made at each end of the press, the nature of these for one end of the press being shown in the drawings, the duplicate set of elements for the other end of the press not being shown. In operating single color work, the printing cylinder 29 operates only in conjunction with the feeding device 27 and is depressed for each period of operation corresponding to the feed from the feeding device 28. It will hence be apparent that the control member 67 must engage the operating lever 51 on each oscillation of the latter in order to depress the printing roll 29 during the proper period; that the printing cylinder 29 must be in its operative position during the period corresponding to the feed from the feeding device 27; and that the trip controlled from the feeding device 27 must throw the printing cylinder 29 out whenever a misfeed occurs in the feeding device 27.

By reference to Figs. 9, 12 and 13, it will be seen that a short shaft 173 passes through

the carrier lever 49 at a point between the two upper arms of the latch levers 68 and 69. On the side of the carrier lever 49 upon which is mounted the control member 64 there is secured to the shaft 173 a lever arm 174 on the end of which is mounted a spring-pressed plunger 175 provided with a handle 176. Two depressions 177 and 178 are formed in the carrier lever 49 into which the 10 spring-pressed plunger 175 may engage, the former when in its inoperative position and the latter when in its operative position. To the opposite end of the shaft 173 are secured two eccentrics, 179 and 180, respectively. 15 To the latch lever 69 is secured a pin 181 positioned to be engaged by the eccentric 180. The eccentric 179 is adapted to engage the lever 121. In its normal inoperative position, the plunger 175 on the lever 174 enters the depression 177 and the flat sides of the eccentrics 179 and 180 come opposite the respective parts 121^b and the arm of latch lever 69, so that the latter elements are not affected by the eccentrics. In changing to 20 single color work, the lever 174 is turned until the plunger 175 engages the depression 178 as shown in Figs. 12 and 13; the eccentric 179 engages the lever 121 and holds it out of interlocking engagement with the lever 49; and the eccentric 180 engages the pin 181 on the latch lever 69, holding it in a 25 position such that it cannot engage the locking shoulder on the control member 67. As a result of this adjustment, the lever 121 cannot interlock with the carrier lever 49 and the latch lever 69 cannot interlock with the control member 67.

The second adjustment to be made is shown more clearly on Fig. 16. The pin 172, which is pushed outwardly by a spring 182, is retracted into a cavity 183 formed in the end of the arm 171 by means of the protruding handle 184. The pin 185 formed on the plunger pin 172 passes out through an 40 opening 186 in the back of the cavity and by rotation of the handle 184 the plunger pin 172 is held in its retracted position. As a result of this adjustment, the operation of the lever 171 cannot affect the extended arm 45 of the latch member 68 when the operating lever 49 is in its lowermost position.

The third adjustment is the movement of the lever 154 (which operates with respect to the control member 67 in the same manner as the lever 131 operates with respect to the control member 64) to such a position that it cannot engage the depending arm of the control member 67. This is effected by extending the link 155 (corresponding to the link 130) beyond its point of engagement with the lever 154 and forming a notch or other suitable means for connection with the lever in the extended portion, as at 189. In making adjustments for single color 50 work, the normal connection between the

lever 154 and the link 155 is disconnected and a new connection made in the notch 189. The lever 154 is thereby pushed back to a position in which it is entirely out of the path of the depending arm of the control member 67.

It will thus be apparent that in normal operation in single color work, with these three adjustments made, the control member 67 is always in engagement with the operating lever 51 and the carrier lever is consequently periodically oscillated, the oscillations corresponding to the periods of feed from the feeding device 28. These oscillations bring the printing cylinder 29 back into operating 55 position during the periods corresponding to the feed from the feeding device 27.

When there is a misfeed from the feeding device 27, the sequence of operations follows that already described for those instances in which a misfeed occurs on the feeding device 27 immediately after a misfeed on the feeding device 28. At the time the misfeed occurs, the operating lever 51 has brought the carrier lever 49 down to its lowermost 60 position. The rod 162 is in position to be engaged by the lever 161, which is operated as a result of the misfeed. The movement of the rod 162 operates the lever 163 to raise the link 163^a and the link 164. The pin 167 65 then engages the depending arm of the lever 168 and the to-and-fro movement of the link 164 draws the lever downwardly, so that its hooked arm engages the pin 67^c on the control member 67, pulling it downwardly. The simultaneous operation of the lever 168, however, is not effective to cause the latch member 68 to unlock the control member 64 and permit its engagement with the carrier lever by reason of the withdrawal of the 70 pin 172 from its engaging position, as explained in connection with Fig. 16. The control member remains in inoperative position and the operating levers oscillate freely without moving the carrier lever 49, which 75 remains in its lowermost position until the operating lever 51 again reaches its lowermost position. Before this time the rod 162 has been released and raised by its spring 162^a, so that the control member 69 is again 80 permitted to engage the carrier lever 49. The latter then resumes its normal oscillating movement.

It is, of course, understood that an entirely 85 similar set of operations takes place at the opposite end of the press for the control of the printing cylinders 30, so as to print during the period of operation corresponding to the feed of sheets from the feeding device 28. It is thus apparent that in single color 90 operation, the two printing rolls may print separate jobs, one on sheets fed from the feeding device 27 and the other on sheets fed from the feeding device 28.

In the printing press illustrated in the 95

drawings, means are provided for the depression of the inking devices simultaneously with the printing cylinders 29 and 30. In the drawings, the mode of operation of this means is illustrated, particularly in connection with the inking devices operating in conjunction with the printing cylinder 29. Particular reference may be had to Figures 1, 8, 10, and 11, the latter figure showing a 10 sectional detail on the line 11—11 of Fig. 10.

The entire inking mechanism operating in conjunction with each printing cylinder is mounted upon a frame work 190 movable longitudinally of the press. Vertically 15 slidable upon each carriage 190 is a support 191 for the ink distributing rolls 192. On each side of the press, each support 191 is provided with a hardened block 192^a in which is a horizontal slot 193. A coil spring 20 194 on each side of the press extends from a projection 195 on the carriage 190 through another projection 196 on the support 191 and exerts its force upwardly against the latter, tending to hold it in raised position. A 25 crank pin 197 secured to a crank 198 on the shaft 199 journaled in the carriage 190 enters the guide slot 193 at each side of the support 191. A lever 200 is secured to the shaft 199 within the latter, and from it a 30 link 201 extends to a lever 202 mounted on a shaft 203, likewise journaled in the carriage 190. To the shaft 203 is secured a second lever arm 204. From this a link 205 provided with a handle 206 extends through 35 and is removably attached to a pin 207 projecting from the eccentric 41 on the shaft 43. In the form illustrated, a notch is provided in the link 205 for engagement with this pin and suitable means are provided for 40 retaining the pin in the notch.

When the eccentric 41 is operated to depress the roll 29, it causes a movement of the link 205 which is transmitted through the lever 204 to the shaft 203, and from this 45 shaft 203 through link 201 to the crank shaft 199. The movement of the crank shaft causes a downward movement of the crank pin 197, which, moving in the guide 193, causes the support 191 to be moved downwardly at the same time as the printing roll 29. It will be noted that the removable link 205 is the sole connection between the inking carriage and the printing press proper. Thus, if it is desired to move back the support 50 for the inking rolls from the press to give access, for example, to the printing cylinder 29, the link 205 is removed from the pin 207 on each side of the press and the support for the inking rolls may then be moved independently of the press.

The foregoing detailed description has been given for clearness of understanding, and no unnecessary limitation should be understood therefrom, but the claims should

be construed as broadly as permissible in view of the prior art.

I claim:

1. In a printing press, an impression cylinder, a printing cylinder normally engaged therewith, an oscillatable shaft, means positively connecting said shaft and printing cylinder to move the latter to and from engagement with the impression cylinder on movement of the shaft, a lever secured to said shaft, a plurality of operating levers 70 oscillatably mounted upon said shaft, means for periodically oscillating said levers at different intervals in the rotation of the impression cylinder, and means for selectively engaging said operating levers with the first 80 mentioned lever to effect oscillatory movement of the shaft.

2. In a printing press, an impression cylinder, a printing cylinder normally engaged therewith, an oscillatable shaft, means positively connecting said shaft and printing cylinder to move the latter to and from engagement with the impression cylinder on movement of the shaft, a lever member secured to the shaft, a plurality of operating 90 levers oscillatably mounted upon said shaft, means for periodically oscillating said levers at different intervals in the rotation of the impression cylinder, means for selectively engaging said operating levers with the first 95 mentioned lever to effect oscillation of the shaft, and means for holding said operating levers, with the exception of the selected operating lever, out of engagement with the lever member.

3. In a printing press, an impression cylinder, a printing cylinder normally in engagement therewith, an oscillatable shaft, means positively connecting said shaft and the printing cylinder, whereby the impression cylinder and the printing cylinder are disengaged and re-engaged on movement of the shaft, a carrier lever secured to said shaft, a pair of operating levers rotatably mounted on said shaft, means for oscillating 105 said operating levers at different angular intervals of rotation of the impression cylinder, means for selectively engaging said operating levers with said carrier lever, and means for preventing simultaneous engagement of both said operating levers with the carrier lever.

4. In a printing press, an impression cylinder, a printing cylinder normally in engagement therewith, an oscillatable shaft, means positively connecting said shaft and the printing cylinder, whereby the impression cylinder and the printing cylinder are disengaged and reengaged on movement of the shaft, a carrier lever secured to said 120 shaft, a pair of operating levers rotatably mounted on said shaft, means for oscillating said operating levers at different angular in-

ervals of rotation of the impression cylinder, means for selectively engaging said operating levers with said carrier lever, and means for releasing the selected operating lever from engagement with the carrier lever at the end of a complete oscillation.

5. In a printing press, an impression cylinder, a printing cylinder normally in engagement therewith, an oscillatable shaft, 10 means positively connecting said shaft and the printing cylinder, whereby the impression cylinder and the printing cylinder are disengaged and re-engaged on movement of the shaft, a carrier lever secured to said 15 shaft, a pair of operating levers rotatably mounted on said shaft, means for oscillating said operating levers at different angular intervals of rotation of the impression cylinder, means for selectively engaging one of 20 said operating levers with said carrier lever, means for releasing the selected operating lever from engagement with the carrier lever during its oscillation and for engaging the other operating lever therewith, 25 6. In a printing press, an impression cylinder, a printing cylinder normally in engagement therewith, an oscillatable shaft, means positively connecting said shaft and the printing cylinder, whereby the impression cylinder and the printing cylinder are 30 disengaged and re-engaged on movement of the shaft, a carrier lever secured to said shaft, a pair of operating levers rotatably mounted on said shaft, means for oscillating 35 said operating levers at different angular intervals of rotation of the impression cylinder, means for selectively engaging said operating levers with said carrier lever, means for disengaging the operating lever 40 and the carrier lever before the movement of the former is completed, and means for engaging the other operating lever with the carrier lever whereby the carrier lever is caused to partake of the movement of the 45 second operating lever.

7. In a printing press, an impression cylinder, a printing cylinder normally in engagement therewith, an oscillatable shaft, means positively connecting said shaft and the printing cylinder, whereby the impression cylinder and the printing cylinder are 50 disengaged and reengaged on movement of the shaft, a carrier lever secured to said shaft, a pair of operating levers rotatably mounted on said shaft, means for oscillating 55 said operating levers at different angular intervals of rotation of the impression cylinder, means for selectively engaging said operating levers with said carrier lever, and means for disengaging the carrier lever and the operating lever before completion of the oscillating movement of the former whereby the carrier lever and the oscillatory shaft are retained in a position of disengagement of

the printing cylinder and the impression cylinder.

8. In a printing press having an impression cylinder and a printing cylinder normally in engagement therewith, means for controlling the movement of the latter, including an oscillatable shaft, a carrier lever secured thereto, a pair of operating levers rotatably mounted on said shaft, means for periodically oscillating said operating levers at different angular intervals of the rotation of the impression cylinder, means for locking the carrier lever in position to hold the printing cylinder in engagement with the impression cylinder, and means for simultaneously releasing said locking means and engaging one of the operating levers with the carrier lever to oscillate the latter.

9. In a printing press having an impression cylinder and a printing cylinder normally in engagement therewith, means for controlling the movement of the latter including an oscillatable shaft, a carrier lever secured thereto, a pair of operating levers rotatably mounted on said shaft, means for periodically oscillating said operating levers at different angular intervals of the rotation of the impression cylinder, means for locking the carrier lever in position to hold the printing cylinder in engagement with the impression cylinder, means for simultaneously releasing said locking means and engaging one of the operating levers with the carrier lever to oscillate the latter, and means for disengaging said operating lever from the carrier lever at the completion of an oscillation of the former, said locking means being re-engaged with the carrier lever.

10. In a printing press having an impression cylinder and a printing cylinder normally in engagement therewith, means for controlling the movement of the latter, including an oscillatable shaft, a carrier lever secured thereto, a periodically oscillating lever rotatably mounted on said shaft, a control member mounted on said carrier lever, said control member being adapted to engage the operating lever to cause the carrier lever to partake of its movement, a latch member normally locking said control member out of engagement with the operating lever, and means for locking the carrier lever in the position corresponding to the normal position of engagement of the impression cylinder and the printing cylinder.

11. In a printing press having an impression cylinder and a printing cylinder normally in engagement therewith, means for controlling the movement of the latter, including an oscillatable shaft, a carrier lever secured thereto, a periodically oscillating lever rotatably mounted on said shaft, a control member mounted on said carrier lever,

5 said control member being adapted to engage the operating lever to cause the carrier lever to partake of its movement, a latch member normally locking said control member out of engagement with the operating lever, means for locking the carrier lever in a position corresponding to the normal position of engagement of the impression cylinder and the printing cylinder, and means for 10 simultaneously releasing said latch member and the locking means whereby the control member engages the operating lever and oscillation of the carrier lever is permitted.

12. In a printing press having an impression cylinder and a printing cylinder normally in engagement therewith, means for controlling the movement of the latter, including an oscillatable shaft, a carrier lever secured thereto, a periodically oscillating lever rotatably mounted on said shaft, a control member mounted on said carrier lever, said control member being adapted to engage the operating lever to cause the carrier lever to partake of its movement, a latch member normally locking said control member out of engagement with the operating lever, a spring pressed lever adapted to engage the carrier lever and lock it in position corresponding to the normal position of engagement of the impression cylinder and the printing cylinder, and means for simultaneously releasing said latch member and said spring held lever whereby the control member engages the operating lever and oscillation of the carrier lever is permitted.

13. In a printing press having an impression cylinder and a printing cylinder normally in engagement therewith, means for controlling the movement of the latter including an oscillatable shaft, a carrier lever secured thereto, a periodically oscillating lever rotatably mounted on said shaft, a control member mounted on said carrier lever, said control member being adapted to engage the oscillating lever to cause the carrier lever to partake of its movement, a latch member normally locking said control member out of engagement with the operating lever, means for releasing said latch member, whereupon the control member engages the oscillating lever at the beginning of an oscillation thereof, and means for disengaging the control member from the oscillating lever upon completion of a single oscillation of the latter, the latch member again locking the control member in inoperative position.

14. In a printing press having an impression cylinder and a printing cylinder normally in engagement therewith, means for controlling the movement of the latter including an oscillatable shaft, a carrier lever secured thereto, a periodically oscillating lever rotatably mounted on said shaft, a

control member mounted on said carrier lever, said control member being adapted to engage the oscillating lever to cause the carrier lever to partake of its movement, a latch member normally locking said control member out of engagement with the operating lever, means for releasing said latch member, whereupon the control member engages the oscillating lever at the beginning of an oscillation thereof, a second lever adapted to intercept the control member during oscillation of the carrier lever, and means for periodically oscillating said second lever to engage the control member as an oscillation of the carrier lever is completed whereby the control member is released from engagement with the oscillating lever and locked in position by the latch member.

15. In a printing press having an impression cylinder and a printing cylinder normally in engagement therewith, means for controlling the movement of the latter, including an oscillatable shaft, a carrier lever secured thereto, a periodically oscillating lever rotatably mounted on said shaft, a control member mounted on said carrier lever, said control member being adapted to engage the operating lever to cause the carrier lever to partake of its movement, means for causing engagement of the control member and the carrier lever, and means for releasing the control member from the operating lever prior to completion of an oscillatory movement of the latter and permitting free movement of the latter.

16. In a printing press having an impression cylinder and a printing cylinder normally in engagement therewith, means for controlling the movement of the latter, including an oscillatable shaft, a carrier lever secured thereto, a periodically oscillating lever rotatably mounted on said shaft, a control member mounted on said carrier lever, said control member being adapted to engage the operating lever to cause the carrier lever to partake of its movement, means for causing engagement of the control member and the carrier lever, a normally inoperative lever in position to engage, when operated, the control member when the latter has partially completed its oscillatory movement, and means controlled by the position of the carrier lever for effecting operation of said lever to engage said control member and release it from the carrier lever.

17. In a printing press, an impression cylinder, a printing cylinder, means for controlling the movement of the printing cylinder into and out of engagement with the impression cylinder, said means including a carrier member, a control member mounted thereon, a periodically oscillating lever, means for engaging the control member

with the oscillating lever to effect movement of the carrier lever, and means operable at the end of an oscillation of said oscillating lever to engage the control member and withdraw it from engagement with the oscillating lever.

18. In a printing press, an impression cylinder, a printing cylinder, means for controlling the movement of the printing cylinder into and out of engagement with the impression cylinder, said means including a carrier member, a control member mounted thereon, a periodically oscillating lever, means for engaging the control member with the oscillating lever to effect movement of the carrier lever, and a periodically oscillating member adapted to engage the control member and withdraw it from engagement with the oscillating lever, said member being timed to operate at the end of the movement of the oscillating lever.

19. In a printing press, an impression cylinder, a printing cylinder, means for moving the latter into and out of engagement with the impression cylinder, said means including an oscillatable shaft, a carrier lever secured to said shaft, a periodically oscillating operating lever on said shaft on each side of said carrier lever, control members secured to the carrier lever on each side thereof, said control members being adapted to engage the operating levers, and means provided on said carrier lever for preventing simultaneous engagement of both said control members with the operating levers.

20. In a printing press, an impression cylinder, a printing cylinder and means for operating the latter to engage and disengage the impression cylinder, said means including a shaft, a carrier lever secured thereto, operating levers, oscillatably mounted on each side of said carrier lever on the shaft, a control member secured to the carrier member on each side thereof, said control members being adapted to engage the corresponding operating levers, and a latch member mounted on each side of the carrier member, each latch member being adapted to engage the control member on its side of the carrier member and lock it out of engagement with the corresponding operating lever.

21. In a printing press, an impression cylinder, a printing cylinder and means for operating the latter to engage and disengage the impression cylinder, said means including a shaft, a carrier lever secured thereto, operating levers oscillatably mounted on each side of said carrier lever on the shaft, a control member secured to the carrier lever on each side thereof, said control members being adapted to engage the corresponding operating levers, a latch member mounted on each side of the carrier member,

each said latch member being adapted to engage the control member on the same side of the carrier member and lock it out of engagement with the corresponding operating lever, and means for normally locking the carrier lever in position.

22. In a printing press, an impression cylinder, a printing cylinder and means for shifting the latter including a shaft positively connected with the impression cylinder bearings, a carrier lever secured to said shaft, a periodically oscillating lever mounted on said shaft, a control member mounted on the carrier lever, means tending to force said control member in engagement with the operating lever, and a latch member mounted on the carrier lever and normally engaging the control member to hold it out of engagement with the oscillating lever.

23. In a printing press, an impression cylinder, a printing cylinder and means for operating the latter to engage and disengage the impression cylinder, said means including a shaft connected with bearings of the printing cylinder, a carrier lever secured to said shaft, a periodically oscillating lever mounted on said shaft on each side of said carrier lever, a control member mounted pivotally on the carrier lever on each side thereof, means tending to force said control members in engagement with said oscillating levers, and a rock-plate mounted on said carrier lever, said rock-plate being positioned to be engaged by either control member when in engagement with the corresponding oscillating lever and to simultaneously engage and hold in inoperative position the control member on the opposite side of the carrier lever.

24. In a printing press, an impression cylinder, a printing cylinder and means for operating the latter to engage and disengage the impression cylinder, said means including a shaft, a carrier lever secured thereto, a periodically oscillating lever mounted on said shaft, a control member mounted on the carrier lever, said control member being adapted to engage the oscillating lever, a latch member mounted on the carrier lever and normally engaging the control member to hold it out of engagement with the oscillating lever, means for locking the carrier lever in the position corresponding to the engagement of the printing cylinder and the tympanum cylinder, and means for simultaneously operating said latch member to unlock the control member and to unlock said locking means holding the carrier lever.

25. In a printing press, an impression cylinder, a printing cylinder and means for operating the latter to engage and disengage the impression cylinder, said means including a shaft, a carrier lever secured thereto, operating levers oscillatably mounted on each side of said carrier lever on the shaft,

5 a control member secured to the carrier lever on each side thereof, said control members being adapted to engage the corresponding operating levers, a latch member mounted 10 on each side of the carrier member, each said latch member being adapted to engage the control member on the same side of the carrier lever and lock it out of engagement with the corresponding operating lever, a spring 15 pressed lever adapted to engage the carrier lever and lock it in one position thereof, and means for selectively engaging one of the latch members to disengage the corresponding control member and for moving said locking lever out of its engagement with the carrier lever.

20 26. In a printing press, an impression cylinder, a printing cylinder and means for operating the latter to engage and disengage the impression cylinder, said means including a shaft, a carrier lever secured thereto, operating levers oscillatably mounted on each side of said carrier lever on the shaft, a control member secured to the carrier lever 25 on each side thereof, said control members being adapted to engage the corresponding operating levers, a latch member mounted on each side of the carrier member, each said latch member being adapted to engage the control member on the same side of the carrier lever and lock it out of engagement with the corresponding operating lever, means for 30 selectively engaging one of said latch members, thereby releasing the corresponding control member and permitting its engagement with an operating lever, and means operating at the end of an oscillation of said operating lever to withdraw the control member from engagement therewith, and 35 means for engaging the latch member with the control member to again lock it out of engagement with the operating lever.

40 27. In a printing press, an impression cylinder, a printing cylinder and means for operating the latter to engage and disengage the impression cylinder, said means including a shaft, a carrier lever secured thereto, operating levers oscillatably mounted on each side of said carrier lever on the shaft, a control member secured to the carrier lever 45 on each side thereof, said control members being adapted to engage the corresponding operating levers, a latch member mounted on each side of the carrier member, means 50 tending to force said latch members into engagement with the corresponding control members, to lock the latter out of engagement with the corresponding operating levers, means for releasing one of said latch members, thereby permitting engagement 55 of the corresponding control member and operating lever, and means operative only during oscillation of the carrier lever for moving said control member out of engagement with the operating lever and into posi- 60

tion to be engaged by the corresponding latch member.

28. In a printing press, an impression cylinder, a printing cylinder and means for operating the latter to engage and disengage the impression cylinder, said means including a shaft, a carrier lever secured thereto, operating levers oscillatably mounted on each side of said carrier lever on the shaft, a control member secured to the carrier lever 70 on each side thereof, said control members being adapted to engage the corresponding operating levers, a latch member mounted on each side of the carrier member, means tending to force said latch members into engagement with the corresponding control members to lock the latter out of engagement with the corresponding operating levers, means for releasing one of said latch members, thereby permitting engagement of the corresponding control member and operating lever, and means operative only during oscillation of the carrier lever for moving said control member out of engagement with the operating lever and into position to be engaged by the corresponding latch member, and means for simultaneously engaging the other latch member to release the corresponding control member and permit its engagement with the corresponding operating lever. 80

29. In a printing press, an impression cylinder, a pair of printing cylinders engaging said impression cylinder at fixed angular intervals, a lever for controlling movement of each of said printing cylinders away from the impression cylinder, push rods, each having one end engaging one of said levers, hammer members having a periodically oscillating movement at intervals corresponding to the angular intervals between the printing cylinders on the impression cylinder, and means for bringing the free ends of the push rods into position to be engaged by the corresponding hammer members, whereby the printing cylinders are successively shifted at the proper angular intervals. 100

30. In a printing press having an impression cylinder, a printing cylinder normally in engagement therewith, means for moving the printing cylinder out of and into engagement with the impression cylinder including a carrier lever positively connected with the printing cylinder, a periodically oscillating lever, a control member on the carrier lever adapted to engage the oscillating lever, and means operable during movement of the carrier lever, while the control member is in engagement with the oscillating lever, to disengage the control member from the oscillating lever. 110

31. In a printing press, an impression cylinder, a printing cylinder normally in engagement therewith, and means for moving the printing cylinder out of and into engage- 120

130

ment with the impression cylinder, said means including a carrier lever positively connected with the printing cylinder, a periodically oscillating lever, a control member on the carrier lever adapted to engage the oscillating lever to effect movement of the carrier member therewith, a normally inoperative releasing lever, and means operable during movement of the carrier lever to bring said releasing lever into engagement with the control member to disengage it from the oscillating lever.

32. In a printing press, an impression cylinder, a printing cylinder normally in engagement therewith, and means for moving said printing cylinder out of and into engagement with the impression cylinder, said means including a carrier lever positively connected with the printing cylinder, a periodically oscillating lever, a control member on the carrier lever adapted to engage the oscillating lever, a normally inoperative releasing lever, a member having a periodical oscillating movement, and means operable during movement of the carrier lever to engage said oscillating member with the releasing lever to bring the latter into engagement with the control member, thereby disengaging it from the oscillating lever.

33. In a printing press, an impression cylinder, a printing cylinder normally in engagement therewith, and means for moving the printing cylinder out of and into engagement with the impression cylinder, said means including a carrier lever, a periodically oscillating lever, means for engaging the carrier lever and the oscillating lever to cause movement of the former, and means for disengaging the carrier lever and the oscillating lever including a rod, a releasing member operated by said rod, a member for engaging and operating the rod, and means for bringing the rod into engagement therewith during movement of the carrier lever.

34. In a printing press, an impression cylinder, a printing cylinder and means for moving the printing cylinder out of and into engagement with the impression cylinder, said means including a carrier lever positively connected with the printing cylinder, a periodically oscillating lever, means for engaging the carrier lever and the oscillating lever to cause movement of the former, and means for disengaging the carrier lever and the oscillating lever, said means including a rod, a releasing member operated by the rod, a member for engaging and operating the rod, and means carried by the carrier lever for holding the rod out of engagement with the operating member when the carrier lever is in position corresponding to the engagement of the printing cylinder and the impression cylinder.

35. In a printing press, an impression cylinder, a printing cylinder and means for

bringing the printing cylinder out of and into engagement with the impression cylinder, said means including a carrier lever positively connected with the printing cylinder, a periodically oscillating lever, means for engaging the carrier lever and the oscillating lever to cause movement of the former, and means for disengaging the carrier lever and the oscillating lever, said means including a rod, a releasing member operated by said rod, a member for engaging and operating the rod, and a projecting shoe carried by the carrier lever and engaging said rod when the carrier lever is in position corresponding to the position of engagement of the printing cylinder and the impression cylinder to prevent engagement of the rod with the operating member.

36. In a printing press, an impression cylinder, a printing cylinder and means for moving the printing cylinder out of and into engagement with the impression cylinder, said means including a carrier lever, a periodically oscillating lever, a control member on the carrier lever adapted to engage the oscillating lever, a normally inoperative releasing lever, a member having a periodical oscillating movement, a rod, means operated by said rod to bring the oscillating member into engagement with the releasing lever to effect operation of the latter, a member for engaging and operating the rod, and means for bringing the rod into engagement therewith during movement of the carrier lever.

37. In a printing press, an impression cylinder, a printing cylinder and means for moving the printing cylinder out of and into engagement with the impression cylinder, said means including a carrier lever, a periodically oscillating lever, a control member on the carrier lever adapted to engage the oscillating lever, a normally inoperative releasing lever, a member having a periodical oscillating movement, a rod, means operated by said rod to bring the oscillating member into engagement with the releasing lever to effect operation of the latter, a member for engaging and operating the rod, and means carried by the carrier lever for holding the rod out of engagement with the operating member when the carrier lever is in position corresponding to the engagement of the printing cylinder and the impression cylinder.

38. In a printing press, an impression cylinder, a printing cylinder and means for moving the printing cylinder out of and into engagement with the impression cylinder, said means including a carrier lever, a periodically oscillating lever, a control member on the carrier lever adapted to engage the oscillating lever, a normally inoperative releasing lever, a member having a periodical oscillating movement, a rod, means operated by said rod to bring the oscillating

- member into engagement with the releasing lever to effect operation of the latter, a member for engaging and operating the rod, a projecting shoe secured to the carrier lever and adapted to engage the rod when the carrier lever is in position corresponding to engagement of the printing cylinder and the impression cylinder, the rod being thereby held out of position for engagement with the operating member.
39. In a printing press, an impression cylinder, a printing cylinder and means for moving the printing cylinder out of and into engagement with the impression cylinder, said means including a carrier lever, oscillating levers, the movement of which corresponds to different periods of rotation of the impression cylinder, control members on the carrier lever adapted to engage the oscillating levers, means for selectively engaging one of the control members with the corresponding oscillating lever, a normally inoperative releasing lever, a member having a periodically oscillating movement, a rod, means operated by said rod to bring the oscillating member into engagement with the releasing lever to effect operation of the latter to release the control member from engagement with the oscillating lever, a member for engaging and operating the rod, means for bringing the rod into engagement therewith during movement of the carrier lever, thereby actuating the releasing lever, and means operated by movement of the releasing lever to engage another control member with the corresponding oscillating lever.
40. In a printing press, an impression cylinder, a printing cylinder normally in engagement therewith and means for moving said printing cylinder out of and into engagement with the impression cylinder, said means including a carrier lever positively connected with the printing cylinder, periodically oscillating levers, the periods of which correspond to different periods of rotation of the impression cylinder, control members on the carrier lever adapted to engage the oscillating levers, a normally inoperative releasing lever, a member having a periodical oscillating movement, means operable during movement of the carrier lever to engage said oscillating member with the releasing lever to bring the latter into engagement with the control member, thereby disengaging it from the oscillating lever, and means operated by movement of the releasing lever to engage another control member with the corresponding oscillating lever.
41. In a printing press, an impression cylinder, a printing cylinder, feeding devices for feeding sheets to said impression cylinder at different periods in the rotation thereof, a carrier lever positively connected with the printing cylinder to control the movement thereof, oscillating levers, the oscillations of said levers being timed to correspond to the periods of feed of said feeding devices, means controlled by misfeed on one of said feeding devices to cause the carrier lever to interlock with the correspondingly timed oscillating lever, and means operable only during movement of the carrier lever by misfeed on the other feeding device to release the carrier lever from the oscillating lever.
42. In a printing press, an impression cylinder, a printing cylinder, feeding devices for feeding sheets to said impression cylinder at different periods in the rotation thereof, a carrier lever positively connected with the printing cylinder to control the movement thereof, oscillating levers, the oscillation of said levers being timed to correspond to the periods of feed of said feeding devices, means controlled by misfeed on one of said feeding devices to cause the carrier lever to interlock with the correspondingly timed oscillating lever, thereby causing movement of the carrier lever, means operable only during movement of the carrier lever by misfeed on the other feeding device to release the carrier lever from the oscillating lever, and means for interlocking the carrier lever with the oscillating lever timed to correspond with the period of feed of the second feeding device.
43. In a printing press, an impression cylinder, a printing cylinder, feeding devices for feeding sheets to said impression cylinder at different periods in the rotation thereof, a carrier lever positively connected with the printing cylinder to control the movement thereof, oscillating levers, the oscillations of which are timed to correspond to the periods of feed of said feeding devices, control members for engaging the carrier lever with said oscillating levers, means controlled by misfeed on one of said feeding devices to cause a control member on the carrier lever to engage the correspondingly timed oscillating lever, thereby causing movement of the carrier lever, and means operable only during movement of the carrier lever by misfeed on the other feeding device to release the control member from the oscillating lever.
44. In a printing press, an impression cylinder, a printing cylinder, feeding devices for feeding sheets to said impression cylinder at different periods in the rotation thereof, a carrier lever positively connected with the printing cylinder to control the movement thereof, oscillating levers, the oscillations of which are timed to correspond to the periods of feed of said feeding devices, control members for engaging the carrier lever with said oscillating levers, means controlled by misfeed on one of said feeding devices to cause a control member on the carrier lever to engage the correspondingly timed oscillating lever, thereby causing

movement of the carrier lever, means operable only during movement of the carrier lever by misfeed on the other feeding device to release the control member from the oscillating lever and means for releasing another control member to engage the oscillating lever timed to correspond with the period of feed on the second feeding device.

45. In a printing press, an impression cylinder, a printing cylinder, means for moving the printing cylinder out of engagement with the impression cylinder, a feeding device for feeding sheets of paper to the impression cylinder and means for controlling the operation of the printing cylinder operating means, said controlling means including a periodically oscillating lever, a movable link adapted in one position to engage the lever and thereby operate said controlling means, a second periodically oscillating lever connected to said link and normally moving it out of engaging position during oscillation of the first mentioned oscillating lever, and means controlled by the sheet feeding device for controlling the operation of the second oscillating lever.

46. In a printing press, an impression cylinder, a plurality of printing cylinders, means for moving each of the printing cylinders out of engagement with the impression cylinder, a feeding device for feeding sheets of paper to the impression cylinder, and means for controlling the operation of each of the means for moving the printing cylinders, said controlling means including a periodically moving member controlled by the sheet feeding device, a movable member connected therewith, a periodically oscillating member adapted to engage said movable member in one position thereof, and means for connecting the movable member with each of said printing cylinder moving means.

47. In a printing press, an impression cylinder, a plurality of printing cylinders, means for moving each of the printing cylinders out of engagement with the impression cylinder, a sheet feeding device, levers, movement of which initiates operation of each of said printing cylinder moving means, a link connecting said levers, a movable member, means connecting said movable member with one of said levers, a periodically oscillating member adapted to engage said movable member in one position thereof, and means controlled by the sheet feeding device for causing movement of said movable member.

48. In a printing press, an impression cylinder, a printing cylinder, means for moving the printing cylinder away from the impression cylinder, sheet feeding devices, each timed to feed sheets to the impression cylinder at different periods in the rotation thereof, means controlled by misfeed on either feeding device to operate the printing cylinder moving means during the period

corresponding to the period of feed of said feeding device, and means controlled by misfeed on the other feeding device operable on successive misfeeds for retaining the printing cylinder out of engagement with the impression cylinder during the period corresponding to the period of feed of the second feeding device.

49. In a printing press, an impression cylinder, a plurality of printing cylinders in engagement therewith, means for moving each of said printing cylinders out of engagement with the impression cylinder, a plurality of sheet feeding means controlled by misfeed on either of sheet feeding means for moving the printing cylinder away from the impression cylinder in succession during the passage of the portion of the impression cylinder to which said sheet feeding device feeds, and means operable on an immediately succeeding misfeed on the other feeding device to hold said printing cylinders out of engagement with the impression cylinder during the passage of the corresponding portion of the impression cylinder.

50. In a printing press, an impression cylinder, a printing cylinder normally in engagement therewith, means for moving the printing cylinder vertically out of engagement with the impression cylinder, said means including a shaft and a crank pin thereon, inking means normally in engagement with the printing cylinder, a vertically movable frame for said inking means, means for moving said frame including an operating lever and a link connecting said separating lever with the crank pin to impart movement to the frame for the inking means synchronously with the movement of the printing cylinder.

51. In a printing press, an impression cylinder, a printing cylinder normally in engagement therewith, means for moving the printing cylinder vertically out of engagement with the impression cylinder, said means including a shaft positively connected with the printing cylinder, a crank pin on said shaft, inking means engaging the printing cylinder, a horizontally movable support for said inking means, a vertically moving frame for the inking means mounted in said support, means for imparting movement to said frame, said means including an operating lever and a link connecting the operating lever with the crank pin, said link having a separable connection with the latter.

52. In a printing press, an impression cylinder, a pair of printing cylinders normally in engagement with said impression cylinder, means for moving each of said printing cylinders out of engagement with the impression cylinder, a pair of sheet feeding devices for feeding sheets to the impression cylinder at different periods in the rotation thereof, and means for op-

erating the means moving one printing cylinder during the passage of the portion of the impression cylinder to which one sheet feeding mechanism feeds, and means 5 for operating the means moving the other printing cylinder out of engagement with the impression cylinder during the period of engagement of the portion of the impression cylinder to which the other sheet 10 feeding device feeds.

53. In a printing press, an impression cylinder, two printing cylinders in engagement therewith, two sheet feeding devices for feeding sheets to the impression cylinder at 15 different periods in the rotation thereof, means for moving each of the printing cylinders out of engagement with the impression cylinder, means for operating said printing cylinder moving means during the 20 passage of the impression cylinder to which said sheet feeding devices feed, one of the printing cylinders being moved away during the period corresponding to the feed of one of the sheet feeding devices and the other 25 during the period corresponding to the feed of the other, whereby each of the printing cylinders is in engagement with the impression cylinder during the period corresponding to the feed of one of the sheet feeding 30 devices, and means operable on misfeed of either feeding device for moving the corresponding printing cylinder out of engagement with the impression cylinder during the period corresponding to the feed of that 35 feeding device.

54. In a printing cylinder, an impression cylinder, a printing cylinder in engagement therewith, a pair of sheet feeding devices, means for moving the printing cylinder 40 away from the impression cylinder, said means including a shaft positively connected with the printing cylinder, an oscillating lever mounted on said shaft, said oscillating lever having a periodical movement corresponding to the feed of sheets from one of 45 said sheet feeding devices, means for locking said oscillating lever to the shaft and means controlled by misfeed from the other feeding device for releasing the oscillating lever from the shaft during the oscillation 50 of the former, whereby the printing cylinder remains disengaged from the impression cylinder during the period corresponding to the feed from the second sheet feeding 55 device.

55. In a printing press, an impression cylinder, a printing cylinder normally in engagement therewith, two sheet feeding devices, means for moving the printing cylinder 60 out of engagement with the impression cylinder, said means including a shaft positively connected with the printing cylinder, a carrier lever secured to said shaft, a periodically oscillating lever mounted on 65 said shaft, the oscillation of said lever cor-

responding to the period of feed of sheets from one of said sheet feeding devices, a control member mounted on the carrier lever, means for engaging the control member with the oscillating lever, thereby locking the latter to the shaft, and means controlled by misfeed from the other feeding device for releasing the control member from the oscillating lever during the oscillation of the latter, thereby retaining the printing cylinder 75 in disengaged position during the period corresponding to the feed from the second sheet feeding device.

56. In a printing press, an impression cylinder, a printing cylinder normally in engagement therewith, two sheet feeding devices for feeding sheets to the impression cylinder, means for moving the printing cylinder out of engagement with the impression cylinder, said means including a shaft positively connected with the printing cylinder, a carrier lever mounted on said shaft, a pair of oscillating levers, each having a periodical oscillation corresponding to the feed 80 from one of said sheet feeding devices, a control member on the carrier lever corresponding to each of said oscillating levers and adapted to engage the corresponding oscillating lever to lock it to said carrier lever, latch members for normally locking said 85 control members out of engagement with the oscillating levers, means controlled by misfeed from the sheet feeding devices for releasing the latch member holding the corresponding control member, and means adjustable to a position such as to permanently 90 release the latch member holding one of said control members.

57. In a printing press, an impression cylinder, a printing cylinder normally in engagement therewith, two sheet feeding devices for feeding sheets to the impression cylinder, means for moving the printing cylinder out of engagement with the impression cylinder, said means including a shaft positively connected with the printing cylinder, a carrier lever mounted on said shaft, a pair of oscillating levers, each having a periodical oscillation corresponding to the feed 105 from one of said sheet feeding devices, a control member on the carrier lever corresponding to each of said oscillating levers and adapted to engage the corresponding oscillating lever to lock it to said carrier lever, latch members for normally locking said 110 control members out of engagement with the oscillating levers, means controlled by misfeed from the sheet feeding devices for releasing the latch member holding the corresponding control member, and means adjustable to a position such as to permanently 115 release the latch member holding one of said control members, and for preventing release of the other latch member.

58. In combination, an impression cylinder 130

- der provided with two impression-surfaces and associated work-holding devices, a pair of co-acting printing cylinders having shiftable bearings, a rock-shaft corresponding 5 with each printing cylinder, eccentrics connecting each rock-shaft with the bearings of each corresponding printing cylinder, a pair of positively driven actuators associated with each rock-shaft, one actuator being timed 10 with respect to a corresponding impression-surface, coupling means for connecting each actuator to the corresponding rock-shaft, and a control mechanism corresponding with each impression-surface and capable of controlling 15 the coupling of an actuator for each rock-shaft, whereby, in case of a misfeed, each printing cylinder may be retracted, in turn, to permit the impression-surface corresponding with the operated control mechanism 20 to pass the printing cylinders without contact.
59. In combination, an impression cylinder provided with two impression-surfaces and associated work-holding devices, a pair 25 of co-acting printing cylinders having shiftable bearings, a rock-shaft corresponding with each printing cylinder, eccentrics connecting each rock-shaft with the bearings of each corresponding printing cylinder, a pair 30 of positively driven actuators associated with each rock-shaft, one actuator being timed with respect to a corresponding impression-surface, coupling means for connecting each actuator to the corresponding rock-shaft, 35 a control mechanism corresponding with each impression-surface and capable of controlling the coupling of an actuator for each rock-shaft, whereby, in case of a misfeed, each printing cylinder may be retracted, in 40 turn, to permit the impression-surface corresponding with the operated control mechanism to pass the printing cylinders without contact, and inter-acting control means, whereby each main control mechanism may 45 interfere in case of a misfeed to the other impression-surface to prevent the return (seriatim) of the retracted cylinders until the second impression-surface passes clear thereof.
60. In combination, an impression cylinder provided with two impression-surfaces and associated work-holding devices, a pair of co-acting printing cylinders having shiftable bearings, counterbalanced springs connected 55 with said bearings and tending to hold the printing cylinders in printing position, a rock-shaft corresponding with each printing cylinder, a pair of actuators corresponding with each rock-shaft and having movements timed respectively with relation to the two impression-surfaces of the impression cylinder, positive connections between each rock-shaft and the bearings of the corresponding printing cylinder, whereby the printing cylinder may be shifted in 60 both directions by the rock-shaft, coupling means adapted to effect the coupling of each actuator associated with a rock-shaft to the corresponding rock-shaft, a control mechanism corresponding with each impression-surface of the impression cylinder and capable of controlling the coupling of an actuator for each rock-shaft, whereby, in case of a misfeed, each printing cylinder may be retracted, in turn, to permit the impression-surface corresponding with the operated control mechanism to pass the printing cylinders without contact, and inter-acting control means, whereby each main control mechanism may interfere, in case of a misfeed to the other impression surface, to prevent 65 the printing cylinder from shifting in both directions by the rock-shaft, and control mechanism adapted to control the coupling of each of the actuators associated with a rock-shaft to the corresponding rock-shaft.
61. In combination, an impression cylinder provided with two impression-surfaces and associated work-holding devices, a pair of co-acting printing cylinders having shiftable bearings, counterbalanced springs connected with said bearings and tending to hold the printing cylinders in printing position, a rock-shaft corresponding with each printing cylinder, a pair of actuators corresponding with each rock-shaft and having movements timed respectively with relation to the two impression-surfaces of the impression cylinder, positive connections between each rock-shaft and the bearings of the corresponding printing cylinder, whereby the printing cylinder may be shifted in both directions by the rock-shaft, coupling means adapted to effect the coupling of each actuator associated with a rock-shaft to the corresponding rock-shaft, and a control mechanism corresponding with each impression-surface of the impression cylinder and capable of controlling the coupling of an actuator for each rock-shaft, whereby, in case of a misfeed, each printing cylinder may be retracted, in turn, to permit the impression-surface corresponding with the operated control mechanism to pass the printing cylinders without contact.
62. In combination, an impression cylinder provided with two impression-surfaces and associated work-holding devices, a pair of co-acting printing cylinders having shiftable bearings, counterbalanced springs connected with said bearings and tending to hold the printing cylinders in printing position, a rock-shaft corresponding with each printing cylinder, a pair of actuators corresponding with each rock-shaft and having movements timed respectively with relation to the two impression-surfaces of the impression cylinder, positive connections between each rock-shaft and the bearings of the corresponding printing cylinder, whereby the printing cylinder may be shifted in both directions by the rock-shaft, coupling means adapted to effect the coupling of each actuator associated with a rock-shaft to the corresponding rock-shaft, a control mechanism corresponding with each impression-surface of the impression cylinder and capable of controlling the coupling of an actuator for each rock-shaft, whereby, in case of a misfeed, each printing cylinder may be retracted, in turn, to permit the impression-surface corresponding with the operated control mechanism to pass the printing cylinders without contact, and inter-acting control means, whereby each main control mechanism may interfere, in case of a misfeed to the other impression surface, to prevent the printing cylinder from shifting in both directions by the rock-shaft, and control mechanism adapted to control the coupling of each of the actuators associated with a rock-shaft to the corresponding rock-shaft.

the return of the retracted cylinders until the second impression-surface passes clear thereof.

63. In combination, an impression cylinder provided with two impression-surfaces and associated work-holding devices, a pair of co-acting printing cylinders having shiftable bearings, a rock-shaft corresponding with each printing cylinder, eccentrics connecting each rock-shaft with the bearings of each corresponding printing cylinder, a pair of periodically oscillated actuators journaled on each rock-shaft, one actuator being timed to correspond with one impression-surface and the other being timed to correspond with the other impression-surface, said actuators thus operating in sequence, coupling means for connecting each actuator to the corresponding rock-shaft, and sheet-controlled mechanism corresponding with each impression-surface and capable of controlling the coupling of an actuator for each rock-shaft, whereby, in case of a misfeed, each printing cylinder may be retracted, in turn, to permit the impression-surface corresponding with the operated control mechanism to pass the printing cylinders without contact.

64. In combination, an impression cylinder provided with two impression-surfaces and with associated work-holding devices, a pair of feed mechanisms, one of said feed mechanisms being adapted to deliver sheets to one impression-surface and the other being adapted to deliver sheets to the other impression-surface, a pair of printing cylinders co-acting with said impression cylinder and provided with shiftable bearings, a rock-shaft corresponding with each printing cylinder, eccentrics connecting each rock-shaft with the bearings of the corresponding printing cylinder, a pair of periodically oscillated actuators associated with each rock-shaft, one actuator being timed with relation to one impression-surface and the other actuator being timed with relation to the other impression-surface, coupling means for connecting each actuator to the corresponding rock-shaft, a sheet-controlled mechanism corresponding with each feed mechanism and capable of controlling the coupling of an actuator for each rock-shaft, whereby, in case of a misfeed, each printing cylinder may be retracted, in turn, to permit the impression-surface corresponding with the operated control mechanism to pass the printing cylinders without contact, and inter-acting control means whereby each main control mechanism may interfere, in case of a misfeed to the other impression-surface, to prevent the return of the retracted cylinders until the second impression-surface passes clear thereof.

65. In combination, an impression cylinder provided with two impression-surfaces and with associated work-holding devices, a

pair of co-acting printing cylinders having shiftable bearings, a rock-shaft corresponding with each printing cylinder and equipped with a fixedly mounted actuating arm, eccentric connections between each rock-shaft and the bearings of the corresponding printing cylinder, periodically oscillated actuators journaled on each rock-shaft on opposite sides of the fixed arm thereof, coupling members interposed between said fixed arm and said actuators, and a control mechanism corresponding with each impression-surface of the impression cylinder and capable of controlling one of the coupling members associated with each rock-shaft.

66. In combination, an impression cylinder provided with two impression-surfaces and with associated work-holding devices, a feed mechanism associated with each impression-surface, a pair of printing cylinders co-acting with said impression cylinder and provided with shiftable bearings, a rock-shaft corresponding with each printing cylinder, eccentrics connecting each rock-shaft with the bearings of the corresponding printing cylinder, a pair of periodically moving actuators associated with each rock-shaft, said actuators moving in sequence, coupling means for connecting each actuator to the corresponding rock-shaft, means for latching the rock-shafts in position corresponding with the printing position of the printing cylinders, and a control mechanism corresponding with each impression surface and capable of controlling the coupling of an actuator for each rock-shaft and effecting also the unlatching of the rock-shafts, whereby, in case of a mis-feed, each printing cylinder may be retracted, in turn, to permit the impression-surface corresponding with the operated control mechanism to pass the printing cylinders without contact.

67. In combination, an impression cylinder provided with two impression-surfaces and with associated work-holding devices, a pair of shiftably mounted coacting printing cylinders, mechanism for effecting shifting of said printing cylinders, a control mechanism corresponding with each impression surface of said impression cylinder and controlling the shifting movements of both printing cylinders, and interacting control means whereby each of the aforementioned control mechanisms may interfere in case of a misfeed to the other impression surface, to prevent the return of the retracted cylinders until the second impression surface passes clear thereof.

68. In combination, an impression cylinder provided with two impression-surfaces and with associated work-holding devices, a pair of shiftably mounted coacting printing cylinders, a rock-shaft corresponding with each printing cylinder and serving to effect the shifting movements thereof, a pair of

positively driven actuators associated with each rock-shaft, one actuator being timed with respect to a corresponding impression surface, coupling means for connecting each actuator to corresponding rock-shaft, a control mechanism corresponding with each impression surface and capable of controlling

the coupling of an actuator for each rock-shaft, and means associated with each control mechanism for preventing the return of ¹⁰ the cylinders after they have been retracted in response to the action of the other control mechanism.

WALLACE S. WARNOCK.
